L. CAMMEN

CENTRIFUGAL CASTING

Filed Nov. 25, 1922

Leon Cammen

INVENTOR.

UNITED STATES PATENT OFFICE.

LEON CAMMEN, OF NEW YORK, N. Y.

CENTRIFUGAL CASTING.

Application filed November 25, 1922. Serial No. 603,275.

To all whom it may concern:

Be it known that I, LEON CAMMEN, a citizen of the United States, and residing in the borough of Manhattan, in the county, city, and State of New York, have invented certain useful Improvements in Centrifugal Casting, of which the following is a specification.

The present invention refers to a mold for casting centrifugally metallic objects which are discontinuous, or whereof the outer surface is generated by a line moving so that it is alternately approaching to, or receding from, the axis of rotation; to the first of these two categories belong such objects as split tubes, or castings being arcs of a circle, or the like; to the second category belong bars, gears, and the like.

20 In the illustrations:

Fig. 1 is a section through the mold in a plane normal to the axis of rotation;

Fig. 2 is a section through a plane comprising the axis of rotation in a direction indicated in Fig. 1 by A—B;

Fig. 3, a section similar to that of Fig. 2, but in a direction indicated in Fig. 1 by C—D.

Attempts to cast centrifugally bars and gears are old, and for example A. E. Fay (Centrifugal casting, Iron Age, February 28, 1901) refers to them in an article more than twenty years old. None of them proved to be successful for the following reason.

In all of these attempts the mold was shaped all the way as shown in cross-section in Fig. 1, and metal was supplied to it while the mold was spinning. Before the metal can reach the bottom of the mold 4, it encounters the rapidly moving projections 6, and the powerful blow of the projections 6 against the stream of molten metal tends to scatter it in a rather fine spray which, as has been found in centrifugal casting, chills while it is in the air, falls back in the form of shot, and is only seldom remelted and fully incorporated into the metal of the casting. Because of this, 50 what is known as "cold shot" is produced in the casting, which means that the casting contains particles of metal which are not homogeneously united to the rest of the metal, but have surfaces of cleavage dividing them therefrom. Such castings are weak mechanically, and in particular can-

not be used for further operations, such as rolling, drawing and forging, as is well known to metallurgists.

The present invention solves this problem by giving the mold such a construction that the metal as it is discharged from the spout does not immediately encounter the partitions 6, but is spread between them gently, so as not to produce any scattering or splashing.

This can be accomplished by adding to the mold having a cross-section shown in Fig. 1, the "bottle-neck" 2—3, shown in Fig. 2. The metal is discharged from the spout into the smooth-bore part 2 of the bottle-neck, where there is nothing to cause the metal to scatter or splash. From this, by the component of centrifugal force acting in the case of liquids along the axis of the mold, the molten metal is propelled into the conical part 3 of the bottle-neck, and thence spreads between the projecting lugs 6. As shown in Fig. 2, the lugs 6 are made to lie snugly against the cone of the bottle-neck some distance below the beginning of the conical shape 3, and if these ends are properly shaped, there is no splashing of the metal.

The cylindrical part 2 of the bottle-neck 55 may be omitted, in which case however there will be more tendency to splash, though even there the splashing may be obviated by careful design of the ends of the lugs 6, and by giving the cone 3 a comparatively small angle of inclination.

It is also possible to omit the conical part 3 of the bottle-neck, but in that case there will be a heavy end plug of the size of the internal bore of 2, which makes it possible 60 to remove the casting only from the pouring end; as a rule, this is not desirable.

In Figs. 1 and 3, 7 indicates the casting or the metal spread between the lugs 6. This represents the case of an ingot or plate 100 casting. The casting of such articles as gears differs from this only by the fact that more metal is supplied to the mold, so much in fact that the lugs 6 are submerged, and the teeth are connected with each other by 105 a ring of metal cast over the lugs 6.

The mold may be cast split in two parts, in which case it is preferable to make the split along the plane A—B, rather than C—D, in order to avoid a fin in the casting. 110 It is also advisable to give the lugs 6 such a shape that the casting should fall out

freely as soon as the rotation of the machine ceased.

In the drawings, the bottle-neck is shown as being made separately from the part of the mold containing the lugs, as this appears to be cheaper and easier from a manufacturing point of view. They can be however made in a single piece if desired.

In the drawings, the bottle-neck part is shown as having a smaller outer diameter than the main part of the mold, i. e., 1. There is nothing to prevent the designer from making them of the same size except considerations of cost and convenience in handling the mold.

It may be added that in pouring large molds of the kind described here, it is advisable to hold the spout not in the center of the part 2, but near, say within 1 inch, of its lower edge, so as to minimize the tendency to splashing.

The present invention has been devised to apply to centrifugal casting on horizontal and inclined axes, the conditions producing splashing in casting on a vertical axis being different from those set forth in this specification, and therefore requiring other remedies to obviate them.

I claim:

1. A mold for centrifugal casting consisting of two parts disposed along the axis of rotation, of which parts the one against which the metal of the casting is fed, has

a smooth internal surface, and the other part has projections of a shape suitable for the desired casting.

2. A mold for centrifugal casting consisting of two parts disposed along the axis of rotation, of which parts the one against which the metal of the casting is fed, has a smooth internal surface of cylindrical shape, and the other part has projections of a shape suitable for the desired casting.

3. A mold for centrifugal casting consisting of two parts disposed along the axis of rotation, of which parts the one against which the metal of the casting is fed, has a smooth internal surface of the shape of a truncated cone contracting towards the pouring end, and the other part has projections of a shape suitable for the desired casting.

4. A mold for centrifugal casting consisting of two parts disposed along the axis of rotation, of which parts the one against which the metal of the casting is fed, has a smooth internal surface of a shape, in the division nearer the pouring end cylindrical, and in the division further away from the pouring end, of a truncated cone contracting towards the pouring end, and the other part has projections of a shape suitable for the desired casting.

Signed in New York, in the county and State of New York, November 24, 1922.

LEON CAMMEN.
